UNITED STATES PATENT OFFICE.

WILLIAM WALTER OWEN, OF OAK PARK, ILLINOIS, ASSIGNOR TO AUTOMATIC ELECTRIC COMPANY, OF CHICAGO, ILLINOIS, A CORPORATION OF NEW YORK.

CALLING DEVICE FOR AN AUTOMATIC TELEPHONE SYSTEM.

Application filed May 26, 1919. Serial No. 299,980.

To all whom it may concern:

Be it known that I, WILLIAM WALTER OWEN, a citizen of the United States of America, and a resident of Oak Park, in the 5 county of Cook and State of Illinois, have invented certain Improved Calling Devices for an Automatic Telephone System, of which the following is a specification.

My invention relates in general to an improved system for simplifying the control 10 of the switches in an automatic system and relates more specifically to an improved calling device which is so arranged and designated as to simplify the directory numbers in a large exchange and to make it much 15 easier to remember the called number.

It will be observed that a feature of importance in the system I specifically herein disclose lies in the fact that I employ a 20 rotary disk rotatable to different distances for sending out sets of impulses of different numbers and that I employ a series of numbers for indicating the different operations of the disk, each number indicating the number of impulses the particular 25 operation produces in the system, and that in addition to these numbers for these operations I also employ a series of descriptive words or names for indicating the different 30 operations of the disk which designate exchanges, so that in preparing the system of numbers for the subscriber I can substitute a name for a digit wherever it is desirable in order that the subscriber's 35 number shall be made as easy as possible to memorize. In other words, the association with each of the numbered impulse-sending operations of the exchange-designating name enables each subscriber's number to be made up of digits and a name 40 or names, the name or names being arranged either at the front of the numbers or in the middle thereof or at the end thereof, as may be considered desirable. Many schemes 45 have been tried out and many applications have been filed in the Patent Office all showing more or less complicated schemes to increase the capacity of the switches or showing complicated calling devices, which must 50 be operated in some peculiar manner. It is well known that in a large automatic telephone system the subscriber is required to remember sometimes as many as eight or 55 more digits in one number. That is, in a 100,000 line exchange five digits would be

necessary, and when, as is often the case, there are numerous private branch exchanges, the number of digits often increases to as many as eight figures, which it will be seen is a very great disadvantage and one 60 to which the subscriber often objects. Among the schemes which have been provided to overcome this difficulty are: dials which have a plurality of series of finger holes some bearing letters and others figures, 65 together with the addition of wiper selecting auxiliary switches, for picking out one of a plurality of sets of wipers in a single switch; also the large dial with the hyphen system has been tried out in which case the 70 number would appear in the directory as 39—46—52, etc., in which case a much larger switch is required. It will be seen that all of these schemes are more or less intricate and require changes in the construction of 75 the standard Strowger type of automatic switch which has been found to be the most efficient, but in no case have words and digits been combined as the index of a given line for automatic calling purposes. 80

My improved method of and means for overcoming this difficulty consists in providing the standard type of calling device as shown in Fig. 1 (only the finger holed disk and the plate of the device being 85 shown) with an inner circle of names such as shown, one name for each of the ten numbered finger holes. These names of course are optional and will in practice be picked to fit the existing offices and parts 90 of the city in which the exchanges are to be installed. One thing which is desirable in selecting these names for the dial is to select a group of names which may be combined in two or perhaps three name combinations such as North-Park-Main or Main-North or South-Park, etc. It will be seen that a great number of names can be found which can be so used. 95

The object of this means for designation 100 is as follows: It is well known that in the manual systems now in use in larger cities it has become common practice to use such called numbers as Central 942, Oak Park 366, etc., the name or name combinations 105 indicating to the operator the particular exchange in which the called number is located. Now it is my intention to apply this same method to the automatic system so that the subscribers may use the same type 110

of numbers to which they are accustomed and may even at times retain their same called numbers when the system is changed over from manual to automatic. In Fig. 5 2 I have shown a diagrammatic trunking diagram of a portion of an automatic system of 100,000 lines and I will explain the application of this improved numbering system in connection with this diagram, 10 although it will be readily seen that this type of calling device and numbering scheme may be easily applied to any size exchange or to any existing exchange in which numbers only are now used.

15 It will be seen that if the subscriber finds a number in his directory listed as Main-North 3, 5 he may then first operate his calling device by inserting his finger in the dial hole opposite the name "Main" then he will 20 operate again by inserting a finger in the hole opposite the name "North" and then the two numbered holes 3 and 5 in proper sequence. In this manner he has in reality called the number 7135 or if the number appears as Main-North-East-35 it will be understood that to the subscriber this number is easier to remember than 71335. Now in a larger exchange where the existing switches call for six or seven digits it will be seen 25 that the number Oak Park 3549 is much easier to remember than 563549 which is actually the number that the subscriber calls when using the dial to call Oak Park 3549. This number may, of course, be still further 30 reduced by using the combination Oak Park-East 549. The subscriber having this number would of course, be located if possible in the South exchange of the territory commonly called Oak Park so that this number 35 would be easily remembered by one who knows that this party lives or has his business in that locality.

Fig. 1 shows a calling device of the type used in my improved system. Fig. 2 shows 45 a trunking diagram by means of which I will illustrate the functions performed by the calling device of Fig. 1.

Referring to the trunking diagram shown on Fig. 2, I have shown a calling subscriber 50 A having access in the usual manner through a line switch C, which may be of any well known type, to a plurality of selector switches D of the Strowger type. This selector D has its levels so arranged, as is 55 common practice, that the first level for instance leads to a number of second selectors E which have access to third selectors F which in turn have access to connectors H all in the first 10,000 group of lines; also 60 the second level of the selectors D lead to second selectors E' which have access to the subscribers of the second 10,000 group of lines, while the third level of the selectors D leads to selectors E'' which have access to 65 subscribers in the third 10,000 group

through third selectors I and connectors H². It will of course be understood that the system is arranged in decimal order and that although I have shown only three levels of trunks for each switch in the system, there 70 will of course be ten levels and the drawing is therefore arranged on the proportion of 3 to 10.

Now it will be seen that to call one of the subscribers L who is located in the first 75 hundred of the third 1,000 of the first 10,000, a subscriber must operate his calling device to step a switch D to its first level to automatically select an idle one of the second selectors E. The selector E is then operated 80 by three impulses from the dial to pick out the third level of trunks leading to the third selectors F². The selector F² must then be operated to its first level and an idle connector H in this level is selected. After the 85 switch H is seized the subscriber may call any number from 11 to 00 to select any line in this particular hundred. Thus the called number of one of these subscribers would in the existing systems be 13155 or a similar 90 number. In the same manner one of the subscribers in the group R will have a call number of say 23111 or 23155, the last two numbers determining the particular line in that hundred. Now, suppose the subscribers 95 in the L group are located in the north-east part of the city, then the dial will be designated as shown with the name "North" opposite the number one dial hole and with the name "East" opposite the number 3 dial 100 hole. Now it may be seen that a subscriber in the L group will appear in the directory as "North East 155," in fact any of the subscribers in any of the ten groups such as L, 105 M and N in this thousand may have the prefix "North East" and a three digit number from 11 to 999.

It will be understood as before pointed out that when the subscriber dials the number "North East 155" he in reality sends 110 the digit 13155 by his dial but that the new number is much easier to remember.

Also the subscribers in any of the thousands consisting of groups R, S and T may use the prefix South East which is the same 115 as 23. In this way it will be seen that the directory may be made up of certain distinctive called numbers a few examples of which are Oak Park 155, which is 56155, Oak Park-North 155, which is 561155, 120 North-Park 155, which is 16155, East Branch 155, which is 38155, etc., and that this combination is very flexible and will greatly simplify the numbering system now in use by the use of a system which is already well known to the mind of a subscriber in manual systems, and also the fact will be obvious that this numbering scheme may be applied to any existing system of standard type without in any way 125 130

changing the central office equipment and that this scheme consists of using a called number in which certain names are substituted for the numbers and form a very easily remembered designation which may be suggestive of the location of the called line.

Having fully described the features and aspects of my invention, what I consider to be new and desire to have protected by Letters Patent will be pointed out in the appended claims.

What I claim as my invention is:

1. In a telephone system, major groups of subscribers' lines, minor groups of subscribers' lines into which one of the major groups is divided, a first switch for electing a major group, a second switch for electing a minor group, each major group and each minor group having a name, a calling device, a rotatable dial therefor, a series of finger holes in said dial, said finger holes marked with said names, means for controlling the first switch by dialing the name of the major group, means for controlling the second switch by dialing the name of the minor group, and other switches controlled by said calling device to complete a connection.
2. In an automatic telephone system comprising automatic switching mechanism for interconnecting calling and called lines, a plurality of exchanges each having a distinctive name adapted for combination with the other names to form intelligible compound names, a calling device for operating the automatic switches, and a rotatable dial for said device having a series of finger holes marked in accordance with the said distinctive names.
3. In an automatic telephone system comprising automatic switching mechanism for interconnecting calling and called lines, a plurality of exchanges, each designated by a distinctive name, a calling device for operating the automatic switches, a rotatable dial for said calling device having a series of finger holes marked in accordance with the ten digits, certain of the said holes being also marked in accordance with the names of said exchanges, word designations for the remaining finger holes which are adapted to form logical combinations with the names of said exchanges, and a plurality of other exchanges designated by said combinations.
4. In an automatic telephone system comprising automatic switching mechanism for interconnecting calling and called lines, a plurality of exchanges, each designated by a distinctive name, a calling device for op-

erating the automatic switches, a rotatable dial for said calling device having a series of finger holes marked in accordance with the ten digits, certain of the said holes being also marked in accordance with the names of said exchanges, word designations for the remaining finger holes which are adapted to be combined with the said exchange names to form intelligible compound names, and a plurality of other exchanges designated by said compound names.

5. In an automatic telephone system comprising automatic switching mechanism for interconnecting calling and called lines, a plurality of main exchanges, each designated by a distinctive name, a calling device for operating the automatic switches, a rotatable dial for said calling device having a series of finger holes marked in accordance with the ten digits, certain of said finger holes being also marked in accordance with the names of said main exchanges, word designations for the remaining finger holes which are adapted for combination with the names of said main exchanges to form compound names suitable for branch exchanges, and a plurality of branch exchanges designated by the compound names so formed.

6. The method of dialling in a mechanical switching system in which subscribers are designated by combination of office names and numbers, which consists in applying to each office a name which is descriptive of the geographical location of the office, in dialling the office name, and then successively dialing the digits of the number of the subscriber's designation.

7. The method of directly operating switches to establish a connection in a mechanical switching system in which subscribers are designated by combination of office names and numbers, and in which the switches are operated in response to the transmission of varied groups of impulses, each group of impulses representing either a name or a digit, which consists in applying names to the offices which are descriptive of the geographical location of the subscribers in that office, in transmitting a succession of groups of impulses corresponding to a plurality of said office names, and then transmitting successive groups of impulses corresponding to the digits of the number of the subscriber's designation.

Signed at Chicago, Cook County, Illinois, this 23rd day of May, 1919.

WILLIAM WALTER OWEN.
